PHOTOGRAPHIC VIEWING APPARATUS

Alvin E. Schubert, Rochester, and Wade S. Nivison, New York, N. Y., assignors to Eastman Kodak Company, a corporation of New Jersey

Application March 12, 1949, Serial No. 1,374

Term of patent 14 years

(Cl. D61—1)

To all whom it may concern:

Be it known that we, Alvin E. Schubert and Wade S. Nivison, citizens of the United States of America, residing in Rochester, county of Monroe, State of New York, and in New York, county of New York, State of New York, respectively, have invented a new, original, and ornamental Design for Photographic Viewing Apparatus, of which the following is a specification, reference being had to the accompanying drawing, forming a part thereof, in which

Fig. 1 is a perspective view of the front and right sides of a photographic viewing apparatus, showing our new design and in which the screen turret is aligned with the base;

Fig. 2 is a perspective view of the front and right sides of our photographic viewing apparatus and in which the screen turret is shown in one of its positions upon rotation thereof to the left;

Fig. 3 is a perspective view of the front and left sides of our photographic viewing apparatus

and in which the screen turret is shown in one of its positions upon rotation thereof to the right; and

Fig. 4 is a rear elevation of our photographic viewing apparatus as shown in Fig. 1.

We claim:

The ornamental design for a photographic viewing apparatus, as shown and described.

ALVIN E. SCHUBERT.
WADE S. NIVISON.
